UNITED STATES PATENT OFFICE.

JAMES J. WOOD, OF BROOKLYN, ASSIGNOR TO FULLER ELECTRICAL COMPANY, OF NEW YORK CITY, N. Y.

ELECTRIC LAMP.

SPECIFICATION forming part of Letters Patent No. 233,589, dated October 19, 1880.

Application filed July 19, 1880. (No model.)

To all whom it may concern:

Be it known that I, JAMES J. WOOD, of Brooklyn, Kings county, New York, have invented certain new and useful Improvements 5 in Electric Lamps, of which the following is a specification.

This invention applies more especially to those lamps which employ approaching carbon points, with a regulating-magnet in circuit 10 therewith to control the approach or separation of the points, and thus keep their distance uniform, so as to render the light formed between them steady, and also to such systems of lighting as employ a number of such lamps 15 in circuit with one generator.

My present invention relates to an improved means of maintaining the resistance of the entire circuit uniform, notwithstanding the occasional or momentary extinguishment of one or 20 more of the lamps, by causing a resistance-coil equaling the resistance of the lamp to be thrown into the circuit when the lamp corresponding thereto becomes thrown out of circuit by the extinguishment of its arc from any 25 of the usual causes. Heretofore such resistance-coils have been thrown into circuit by the action of a magnet or similar device additional to the usual regulating mechanism of the lamp, which thus not only adds to the compo- 30 sition of the lamp, but forms an additional resistance in the normal circuit thereof.

Now, my invention is distinguished by organizing the usual regulating-magnet of the lamp, or the armature thereof, to act as a contact maker and breaker to throw the resistance-coil into circuit when the armature retires fully from the magnet, as the latter loses its power by the extinguishment of the arc, and on the other hand to throw said coil out 40 of circuit as soon as the current is again established through the magnet and carbons, thus rendering the lamp not only very efficient, but more cheap, simple, and compact, and enabling the same mechanism to perform 45 several functions without discordance.

The figure in the annexed drawing presents an elevation of a lamp of the usual type embodying my improvement.

l indicates the regulating-magnet, which is 50 in circuit with the carbons, as usual. The armature *m* of this magnet is fixed to a tilting

frame, *h*, which carries a train of gearing meshing with a rack on the positive carbon-holder, so that when the current flows through the magnet and carbons to form the light the armature is attracted, the frame *h* tipped, and the carbon raised to give the proper separation to form the arc between the points, this movement bringing the escape-wheel *h'* of the train against the fixed stop-tooth *f*, so as to prevent any descent of the carbon. When, however, the separation of the points becomes too great, the current and magnetism become correspondingly weakened, and the spring *g* will then overcome the magnet, tip the frame in the opposite direction, depress the carbon-holder, release a few teeth of the gearing, and thus give the necessary feed to keep the points at the normal distance. Should, however, the arc between the carbon points become entirely extinguished 70 by the wind or other cause, the magnet *l* will then, of course, lose all its power, and the spring *g* will cause the armature to retire fully from the magnet and tip the tilting frame *h* into contact with its limiting-stop *A*. This movement will, of course, release the train of gearing and permit the upper carbon to descend slowly and touch the lower carbon, so as to again establish the current through the magnet and carbons and again form the arc in the usual manner. It may be observed, however, that before the arc could be thus established a break in the circuit would exist for an interval of time, which, if no other passage of equal resistance for the current to the lamp were 85 provided, would seriously affect the action of the generator, and also all the other lamps in the circuit, if not entirely derange their action. According to my invention, therefore, I cause the retiring motion of the armature *m* or its 90 tilting frame *h* against the stop *A* to serve as a contact-maker to throw a coil into circuit having a resistance equal to the normal arc, or thereabout, which coil is again thrown out of circuit as soon as the current is established 95 through the magnet, and the carbons and the light formed thereby, thus obviating all the above-named objections.

In the drawing, *B* indicates the resistance-coil, which is preferably wound upon but insulated from the tube or rod *k*, by which the lamp is suspended, this arrangement of the

coil being obviously compact and convenient. One end of this coil connects to the insulated or negative binding-post on the head of the lamp-frame, which post also connects, as usual, 5 to one end of the magnet-coils, the opposite end of which connects to the lower carbon. The other end of the resistance-coil connects with the stop-screw A of the tilting armature-frame *m h*, which screw, instead of being in 10 metallic connection with the lamp-frame, as heretofore, is insulated therefrom, as indicated; but the armature-frame *m h* is in metallic connection with the frame, as usual. Now the suspending-rod *k*, on which the resistance-coil 15 is wound, is in metallic connection with the lamp-frame, and the positive circuit-wire is therefore preferably connected to the base of this tube, while the negative wire connects to the negative post insulated on the lamp-frame. 20 Hence, when the lamp is in action and the arc formed, the current enters through the suspending-rod *k* through the frame of the lamp, the upper carbon - holder, and carbon, and, 25 passing to the lower carbon, returns through the coils of the regulating-magnet *l* and flows off by the negative post. While the current therefore takes this its usual course to form 30 the light, the attraction of the magnet will withdraw the armature-frame *m h* out of contact with the stop A, and the slight oscillations of the armature - frame under the varying 35 attraction of the magnet and the opposing action of the spring *g* will regulate the feed and separation of the carbons and keep the arc uniform in the usual manner. Should, however, the arc become entirely extinguished—say by a sudden gust of wind—the magnet will at once lose its power and the spring *g* will throw the armature-frame in contact with the stop A, so that the current will then find a passage from the armature-frame 45 through the stop A, the resistance - coil B, and off through the negative binding - post, through which it will continue to flow till the positive carbon has descended and touched the lower carbon, when, the current finding its normal passage, the magnet will be energized so as to attract the armature, break the circuit with the resistance-coil, and raise the carbon to give 50 the proper separation to form the arc, and thus again establish the light. Hence, by this means, while any lamp or number of lamps in the circuit are extinguished, the action of the generator or of the other lamps will not be 55 effected for as one or more lamps become extinguished an equivalent resistance is immediately introduced into the circuit, thus rendering the resistance of the entire circuit and

of any section thereof uniform and constant and preventing any breaks in the circuit.

60

It may be further observed that my means of accomplishing these results adds little or nothing to the ordinary mechanism of the lamp, but greatly increases its value and efficiency without interfering in the least with 65 any of the usual functions of the ordinary regulating mechanism.

I do not, of course, limit myself to any special form of regulating-magnet, or armature, or mechanical mechanism, as the essence of 70 my invention consists simply in so organizing the regulating mechanism that the armature or other movable part actuated by the regulating-magnet and a retiring force makes contact with a stop and throws the resistance into 75 the circuit when the attraction of the regulating-magnet fails. A solenoid may therefore be used in lieu of an ordinary electro-magnet, and the form of the armature or other part moved or actuated by the magnet or solenoid, 80 as also of the general mechanical mechanism, may, of course, be greatly varied, as experts in the art will readily understand, without making any departure from the spirit of my invention.

85

In lieu of the coil of wire B, any conductor of equivalent resistance may, of course, be used; but the coil is preferable.

What I claim as my invention is—

1. An electric lamp, substantially such as 90 described, having the armature or equivalent movable or actuated part of its regulating-magnet organized to act as a contact-maker, to throw a resistance-coil or equivalent conductor equal to the normal arc, or thereabout, 95 into circuit when the said part retires fully from the magnet, substantially as and for the purpose set forth.

2. In an electric lamp substantially such as 100 described, the combination, with the regulating-magnet thereof and its armature or equivalent, arranged in the general circuit, and a conducting-stop against which such armature retires, of a resistance-coil or equivalent conductor having one end in the general circuit 105 and the opposite end connected with said stop, substantially as and for the purpose herein shown and described.

3. In an electric lamp, a resistance - coil wound upon the rod or tube whereby the lamp 110 is suspended, substantially as and for the purpose set forth.

JAMES J. WOOD.
